UNITED STATES PATENT OFFICE.

ALLAN S. HUSTED, OF CHICAGO, ILLINOIS.

INTERNAL-COMBUSTION ENGINE.

1,270,295.

Specification of Letters Patent. Patented June 25, 1918.

Application filed April 26, 1915. Serial No. 23,852.

To all whom it may concern:

Be it known that I, ALLAN S. HUSTED, a citizen of the United States, residing at Chicago, in the county of Cook and State of Illinois, have invented a certain new and useful Improvement in Internal-Combustion Engines, of which the following is a full, clear, concise, and exact description, reference being had to the accompanying drawings, forming a part of this specification.

This invention relates to improvements in internal combustion engines.

One object of the invention is to provide an internal combustion engine, and more particularly a gasoline engine for automobile use, in which a complete scavenging of the cylinder is obtained during each cycle of operations, the engine operating on the two cycle principle.

Other objects of the invention are to provide an engine of the character described which is of compact arrangement; which employs an auxiliary or scavenging piston movable on the power stroke with the power piston and independently movable of the latter on the return stroke; which has a scavenging piston having a longer stroke than that of the power piston; which employs self-contained, self-actuated means for operating the auxiliary or scavenging piston on its return strokes, which means are confined within the power piston; which is provided with a single member controlling the valves and ports of intake and exhaust; which will run at a lower speed than the ordinary 4 cycle type engine; which is provided with automatically operated means governing the speed of the auxiliary piston; which is provided with intake and exhaust ports of relatively large area; and which consists of relatively few parts, simply arranged.

The invention furthermore consists in the improvements of the parts and devices and in the novel combinations of the parts and devices, as herein shown, described or claimed.

In the drawing forming a part of this specification, I have illustrated one embodiment of my invention and in said drawings Figure 1 is a vertical central sectional view of an engine employing two power cylinders arranged in tandem, the parts being shown in the position when an explosion is about to take place in the upper cylinder. Fig. 2 is a view similar to Fig. 1 but showing the

parts after the explosion in the upper cylinder has taken place and the power piston has traveled about half of its stroke. Fig. 3 is a view similar to Figs. 1 and 2 but showing the end of the downward stroke of the piston and with the auxiliary piston for the upper cylinder returned to its full height, the auxiliary piston in the lower cylinder being also moved up from its lowermost position, as shown in Fig. 1, and the parts so arranged that an explosion is about to take place in the lower power cylinder. Fig. 4 is a side elevation of the structure illustrated in Figs. 1, 2 and 3. Figs. 5, 6 and 7 are enlarged transverse sectional views taken substantially on the lines 5—5, 6—6 and 7—7, respectively, of Fig. 1, and Fig. 8 is an enlarged detail sectional view to more clearly illustrate the ports and passages of one of the power pistons, its associate auxiliary piston and the head of the cylinder.

Referring to said drawing, the main casting having two power cylinders formed therein is designated generally by the reference A, and as shown, has the heads A' A' bolted thereto. The casting A is provided with an upper power cylinder B and a lower power cylinder B'. Mounted within the power cylinders and reciprocating back and forth therein, in the usual manner, is a double ended power piston designated generally by the reference C, and, as shown, the same comprises a single casting having an upper power piston D and a lower power piston D', the latter being each provided with a hollow, rigid sleeve 10 which communicates with a central chamber 11, the sleeves 10 each forming air cylinders within which reciprocate air pistons E and E', each air piston being connected by a piston rod 12 with its corresponding auxiliary or scavenging piston F and F', the auxiliary pistons F and F' being interposed between their corresponding power pistons and the heads of the power cylinders. The double ended piston C is also provided with an integral transversely extending bearing 13 for the piston pin 14 working in slots 114 in the casting A and to which is connected oppositely disposed pitmen 15—15 (see Fig. 4) the lower ends of said pitmen being connected to cranks on the power shaft, not shown, as will be understood. The air cylinders 10 and chamber 11 are closed, except for ports at the outer ends of each of the cylinders 10, as will be explained herein-

after. In the head of each power cylinder is provided a spark plug 16, of any desirable type, and connected to a source of current in the usual manner. The explosive mixture is admitted through a manifold 17 which communicates with passages 18-18 formed in jacket of the power cylinder and having inlet ports or intakes 19-19 adapted to communicate with the power cylinders B and B'. The casting A is also provided with suitable water jacket spaces 20-20 for cooling purposes in the usual manner. As will be noted, the intake ports for the explosive mixture are so located as to be uncovered when each power piston is at the end of its out or power stroke. A plurality of exhaust ports 21-21 are provided for each power cylinder, which exhaust ports are located closely adjacent the heads of the cylinders, it being understood that a plurality of such exhaust ports, as well as intake ports, are provided for each cylinder, the same being arranged circumferentially of the cylinders and communicating with each other.

Interposed between the various pistons and the walls of the power cylinders is a cylindrical sleeve 22 having the ends thereof slidable in suitable recesses 23-23 in the heads of the cylinders, said sleeve 22 having a limited reciprocating movement, the timing of which is governed by cams on the crank shaft (not shown) through the intermediary of rods 24 which connect with the sleeve and pass through the lower cylinder head (see Figs. 1, 2 and 3). Said sleeve 22 is provided with an upper and lower series of circularly arranged intake ports 25-25 adapted to align, at the proper time, with the intake ports 19-19. Near each of its outer ends the sleeve 22 is also provided with a series of circularly arranged exhaust ports 26-26 adapted to be aligned, at the proper time, with the exhaust ports 21-21 of each power cylinder. In order to prevent the admission of the explosive mixture below the power pistons upon their respective return or in-strokes, each power piston D and D' is provided with a skirt 27-27 which covers the ports 25-25 in the sleeve. In order to open the spaces between the cylinder 10 and the sleeves 27 to the atmosphere, the sleeves 27 and sleeve 22 are suitably slotted in alignment with the slots 114, that is, directly in back of the cylinder 10 as the latter is viewed in Fig. 1. Near each end of the sleeve 22 it is provided with a series of circularly arranged bypasses 28-28, for a purpose hereinafter described. Said sleeve 22 is also provided near each end thereof with a shouldered, inwardly projecting annular rib 29, suitable recesses 30 being provided in each head of the cylinder to accommodate said rib. The outer face of each auxiliary piston F and F' is also provided with a shouldered, annular rib 31, adapted to be engaged and

actuated by the corresponding annular rib 29 of the sleeve.

On the inner side of each main piston D and D', near the outer end of its corresponding air cylinder 10, is provided a plurality of air ports 32 communicating with the atmosphere outside of the piston C. Each main piston D and D', on its under side, is also provided with one or more air passages 33 (see Fig. 8) which extend to the periphery 75 of the piston proper and at certain portions of the stroke of the piston are adapted to register with ports 34 and 35 formed in the sleeve 22 and cylinder casting A respectively, it being understood that the passages 33 and 80 ports 34 and 35 are similarly arranged for each power cylinder.

In each cylinder head I provide packing rings 36; all of the pistons are provided with suitable packing rings; and packing glands 85 37 are inserted in each of the main pistons for co-operation with the auxiliary piston stems 12-12.

The operation is as follows: Assuming the parts in the position shown in Fig. 1 and 90 with a fresh explosive mixture compressed between the auxiliary piston F and the head of the cylinder B. Upon an explosion of said mixture, the auxiliary piston F and the main piston D are impelled downwardly or, 95 for convenience of expression and to make the description applicable to both ends of the engine, on their out or power stroke. As the auxiliary piston F and power piston D travel together under the impulse of the explosion, it is obvious that the air which is contained within the lower air cylinder 10 and chamber 11 will be compressed, due to the fact that the lower air piston E' moves relatively inwardly of the descending lower 100 air cylinder 10, (see Fig. 2 where the parts are shown with the piston D approximately at half stroke). Upon a continuation of the downward movement of the pistons F and D, the air in the chamber 11 will be still 110 more compressed and when, near the end of the outer or power stroke of the piston D, the sleeve 22 has been raised so that the upper ports 26 thereof align with the exhaust ports 21, the pressure in the cylinder B will 115 be relieved and the air which is compressed within the air chamber 11 will expand and automatically push the auxiliary piston F upwardly until it engages with the head of the cylinder B, which is the position shown 120 in Fig. 3. During the final portion of the outer or power stroke of the piston D and during the initial portion of its return stroke, the intake ports 25-25 of the sleeve 22 are in communication with the intake ports 19-19 and thus a fresh charge of the explosive mixture is drawn in by the upwardly moving auxiliary piston F between the main or power piston D and the under side of the auxiliary piston F, see Fig. 3. The timing 130

of the auxiliary piston F and the power piston D is such that the former reaches its uppermost position substantially at the same time that the latter reaches its lowermost 5 position. As the cycle of operations continues, the auxiliary piston F is slowly lowered by being actuated by the sleeve 22 and the power piston starts on its return or in-stroke. During this relative approaching 10 movement of the auxiliary piston F and power piston D, the new charge is compressed therebetween and the mixture is forced through the by-passes 28-28 until the same is gradually displaced from the 15 space between the auxiliary and the power piston to the compression space above the auxiliary piston, whereupon the next explosion takes place and the cycle of operations is repeated.

20 The foregoing described operation is based on the assumption that the engine is running. When the engine is started, and there is no explosive mixture in either of the power cylinders, the engine may be cranked 25 in the usual manner, whereupon the following action occurs:

Assuming the parts as shown in Fig. 1 and confining the description to the upper cylinder, as before, as the power piston is forced 30 downwardly by the cranking operation, the auxiliary piston F will lag somewhat and leave a space between it and the power piston. As the power piston is lowered so as to uncover the intake ports, the partial vacuum 35 between the auxiliary piston and the power piston will cause the mixture to be drawn in and upon the return or in-stroke of the power piston this new charge partly mixed with air will be compressed, as heretofore 40 described, and forced around and to the top side of the auxiliary piston. This weak mixture being exploded by the spark, will force the auxiliary and power pistons down and if the strength of the explosion is not 45 sufficient to force the auxiliary piston down to its lowermost intended stroke, a greater vacuum than before will be created between the auxiliary piston and the power piston due to the fact that the auxiliary piston having 50 been forced down farther will have compressed the air in the cylinder more, and consequently upon expansion of the air, the auxiliary piston will be forced farther away from the head of the power piston. A 55 greater quantity of the explosive mixture will, therefore, be drawn in when the intake ports are uncovered. The up-stroke of the power piston will of course compress the charge and force it to the top side of the 60 auxiliary piston, in the manner heretofore described, and upon being ignited the explosion will force the auxiliary and power pistons down. In this way, one or two turns 65 of the crank shaft will be sufficient to start the engine, as will be understood.

It is also apparent that in the operation of the engine, the return independent stroke of the auxiliary pistons is facilitated, due to the fact that there will be a partial vacuum on the outer sides of the air pistons E and 70 E', that is, between said air pistons and the heads of the power pistons.

Although the preceding description of the operation has been confined to the upper cylinder B, it will be understood that the same 75 series of operations take place with regard to the lower cylinder B' and that therefore the double ended piston C is given an impulse at the beginning of each of its up and down strokes.

It will also be observed that gas cushions, that is either the explosive gas or air or a mixture of both, will be formed between the auxiliary pistons and the power pistons as the two come together; between the air pistons and the heads of the air cylinders or under sides of the power pistons; between the shouldered ribs on the sleeves and the shouldered auxiliary pistons; and also between the auxiliary pistons and the main 80 cylinder heads when the auxiliary pistons have their independent or return strokes. These fluid cushions materially contribute to the smooth running of the engine and minimize the shocks which might otherwise 85 occur should the moving parts be permitted to strike each other at high speed. It has heretofore been stated that the auxiliary pistons draw in the new charges and it will be noted that, on account of the strokes of the auxiliary pistons being greater than that of the power pistons, the charges so drawn in 90 will be larger than is possible in the usual types of internal combustion engines.

Speed regulation of the auxiliary pistons.—In the operation of the engine, when the exhaust ports of the upper cylinder B are opened and the pressure on the outer side of the auxiliary piston F is relieved and the latter is impelled upwardly due to 10 the expansion of the air in the chamber 11 and the partial vacuum on the outer side of the air piston E, the speed of this return or independent movement of the auxiliary piston F is regulated by the air ports 32-32 115 which permit whatever air is on the outer or upper side of the air piston E to escape. The area of these air ports 32, being a constant, will, so far as these ports 32 alone are concerned, result in the return or independent movements of the auxiliary piston F taking place at a uniform rate. When the engine is speeded up, it is necessary that the auxiliary piston F make its return or independent stroke faster than when the engine is running slower and for this reason, the air relief passages 33, 34 and 35 have been provided which, when the engine is running faster, will augment the relief afforded by the air ports 32 at a point in the actually 120 125 130

- elapsed time in the independent stroke of the auxiliary piston relatively sooner than they do when the engine is running slower. In other words, when the engine is running 5 slow the relief afforded by the air ports 32 alone, during the independent stroke of the auxiliary piston F, extends over a longer portion of the actual time consumed by the independent stroke and the relief afforded 10 by the combined air ports 32 and relief passages 33, 34 and 35 over a shorter portion of the actual time consumed by the independent stroke, than when the engine is running faster. 15 From the preceding description it will be seen that the auxiliary pistons completely expel the exploded or burned gases and thus insure a pure mixture for each explosion. The arrangement is also simple 20 and consists of a minimum number of parts, since I employ only one member, namely the sleeve, for operating all the intake and exhaust ports, which sleeve also positively separates the auxiliary pistons 25 from the heads of the cylinders after the burned gases have been expelled to provide compression spaces for the new charges. Another advantage inherent in my construction is the relatively large area of the intake 30 and exhaust ports, thus insuring quick action at all times and in the admission of the new charges of explosive mixture, it is apparent that the same will have a cooling effect on the main or power pistons, since 35 the incoming mixture passes over the top of said pistons.

Another important advantage of my improvement resides in the means automatically operating and governing the scavenging or auxiliary pistons. This air or other fluid medium is contained within the main piston itself, thus minimizing space required, and the same body of air or other elastic fluid is used over and over to operate the auxiliary pistons and the compression of this contained air is automatically obtained by the power generated within the engine and outside source of compressed air or other medium is not necessary or required 50 for the successful operation of these auxiliary pistons.

Another advantage resides in the fact that the stems or rods for the auxiliary pistons are never exposed to the hot exploded mixtures and consequently the same are not subject to corrosion or pitting.

Although I have herein shown and described my improvement in connection with a pair of cylinders arranged in tandem, yet 60 the invention is by no means confined to such an engine but is equally applicable to other engines of either the single cylinder or multiple cylinder arranged side by side, types and I do not wish to be confined to the specific structure herein shown and described,

and contemplate all changes, modifications and variations that come within the scope of the claims appended hereto.

I claim:—

1. In an internal combustion engine, the combination with a cylinder and power piston, of a scavenging piston interposed between the power piston and the head of said cylinder and adapted to engage the latter to thereby expel the burnt gases, a piston rod 70 connected to the said scavenging piston and passing through the head of the power piston, an air piston carried by said piston rod, an air cylinder within which said air piston operates, said air cylinder having its axis coinciding with the axis of the main cylinder, said scavenging piston being movable with the power piston on its power stroke and independently movable thereof on its return stroke, the air in the said air cylinder 75 being compressed on the power stroke of said power piston.

2. In an internal combustion engine, the combination with a cylinder, a main piston coöperable therewith, and an auxiliary piston in the cylinder movable with the main piston on its out strokes, of a movable member outside of said auxiliary piston and having by-passes providing communication between the spaces on opposite sides of the auxiliary piston when the latter is near its innermost position, and yielding means for causing the auxiliary piston to return on its in-stroke and thereby completely scavenge 95 the cylinder.

3. In an internal combustion engine, the combination with a cylinder provided with an exhaust port adjacent its head end and intake port adjacent to the limit of travel of the power piston on its out stroke, a power piston, and an auxiliary piston in said cylinder movable with the power piston on its out or expansion stroke, and air pressure operated means within the power piston for actuating said auxiliary piston on 105 its return stroke and to force the same against the head of the cylinder and thereby expel all the burnt gases.

4. In an internal combustion engine, the combination with a power cylinder, a power piston, of an auxiliary piston, said power piston having an interior air cylinder, an air piston working in said air cylinder adapted alternately to compress the air therewithin and be impelled by the expansion thereof, and a piston rod connecting said auxiliary piston and said air piston, said air cylinder being provided with a plurality of air ports near the outer end thereof, some of said air ports being uncovered 115 on the outer side of said air piston when the latter is at the limit of its stroke after the air has expanded.

5. In an internal combustion engine, the combination with a cylinder, power piston, 120

- and auxiliary piston, the latter being movable with the power piston on the power strokes and independently movable on its return strokes, said cylinder being provided 5 with exhaust ports near the head thereof and with intake ports so located and controlled as to be open when the power piston is near the end of its power stroke, said auxiliary piston returning on its independent 10 strokes in advance of the power piston and thereby drawing in new charges through the intake ports and simultaneously expelling burned gases through the exhaust ports, of a mechanically operated sleeve valve for 15 opening and closing said intake and exhaust ports.
6. In an internal combustion engine, the combination with a cylinder, power piston, and auxiliary piston between the cylinder 20 head and the power piston, said auxiliary piston being movable independently of the power piston on its return stroke, of means for returning the auxiliary piston to the cylinder head in advance of the return 25 stroke of the power piston, and means for separating the auxiliary piston from the cylinder head a short distance during the return stroke of the power piston to provide a compression space, said last named 30 means including a sleeve having ports adapted to register with the cylinder intake and exhaust ports.
7. In an internal combustion engine, the combination with a cylinder, power piston, 35 and auxiliary piston between the cylinder head and the power piston, the auxiliary piston being movable independently of the power piston on its return stroke, of means for returning the auxiliary piston to the cylinder head in advance of the return 40 stroke of the power piston, and means for separating the auxiliary piston from the cylinder head a short distance during the return stroke of the power piston to there- 45 by provide a compression space for the explosive mixture, said last named means including a sleeve valve mechanically operated and movable simultaneously with but in opposite directions to the power piston.
- 50 8. In an internal combustion engine, the combination with a cylinder, power piston, and auxiliary piston, the power piston having a shorter stroke than the auxiliary piston and the latter being adapted to engage 55 with the cylinder head, of mechanism for imparting a relatively short outward movement to the auxiliary piston from the cylinder head prior to the power piston reaching its innermost position to thereby pro- 60 vide a space for the explosive mixture between the auxiliary piston and the cylinder head, said mechanism including a sleeve slidable within said cylinder and having 65 ports adapted to register with the cylinder intake and exhaust ports.
9. In an internal combustion engine, the combination with a cylinder, a sleeve slidably mounted within said cylinder, a power piston mounted within said sleeve, an auxiliary piston interposed between the power 70 piston and the head end of the cylinder, the auxiliary piston and power piston moving together on the power stroke, and means for actuating the auxiliary piston independently of and in advance of the power piston 75 on its return stroke, of means regulating the speed of the return independent strokes of the auxiliary piston, said means includ- ing relief ports carried by said sleeve.
10. In an internal combustion engine, the combination with a cylinder having exhaust ports near its head end and intake ports near its opposite end, a slidable sleeve valve mounted within said cylinder and having ports adapted to register with said intake 80 and exhaust ports, a power piston, and an auxiliary piston movable with the power piston on its power strokes and independently movable thereon on its return strokes, of fluid pressure means for imparting the 85 independent return strokes to the auxiliary piston, said sleeve being simultaneously movable with but in opposite directions to the power piston and adapted to actuate the auxiliary piston away from the head end of 90 the cylinder to thereby provide a compres- 95 sion space, during the return stroke of the power piston.
11. In an internal combustion engine, the combination with a power cylinder, a slidable sleeve valve mounted within said cylinder, the cylinder having intake and exhaust ports and the sleeve corresponding ports adapted to register therewith, a power piston having an air cylinder, an auxiliary piston interposed between the power piston and the head end of the cylinder, an air 100 piston mounted within said air cylinder and connected with the auxiliary piston, said auxiliary piston being movable with the 105 power piston on the power strokes, means for compressing the air within said air cylinder, the expansion of the air within said air cylinder impelling the auxiliary piston to the head end of the power cylinder in ad- 110 vance of the return stroke of the power piston, and mechanism for reciprocating said sleeve, said sleeve engaging the auxiliary piston to move it away from the head end 115 of the cylinder and thereby provide a com- 120 bustion space during the return stroke of the power piston.
12. In an internal combustion engine, the combination with a power cylinder having a spark plug located centrally of the head 125 thereof, said cylinder having a plurality of exhaust ports adjacent the head, and a plurality of intake ports adjacent the outer limit of travel of the power piston, and a power piston, of an auxiliary piston, a sleeve 130

- valve slidably mounted within the cylinder and having ports adapted to register simultaneously with the corresponding intake and exhaust ports of the power cylinder, said 5 sleeve valve being provided adjacent its head end with an inwardly projecting shoulder adapted to engage said auxiliary piston and draw it a short distance away from the cylinder head to thereby form a 10 compression space, said sleeve being also provided with a plurality of longitudinally arranged grooves passing around said shoulder and adapted to transfer the explosive mixture around the head of said auxiliary piston.
- 15 13. In an internal combustion engine, the combination with a power cylinder having a plurality of exhaust ports adjacent the head thereof, and a plurality of intake ports adjacent the outer limit of travel of the power piston, and a power piston, of an auxiliary piston, and a sleeve valve, said power piston being connected with the crank shaft, and having contained within itself an 20 air cylinder which coacts with the auxiliary piston, and provided adjacent the inner end thereof with a plurality of air release holes and passages, the latter extending through the metal of the power piston to its periphery, and adapted to register with corresponding holes in said sleeve valve to thereby furnish additional means of exit for air from said air cylinder.
- 25 14. In an internal combustion engine, the combination with a cylinder, power piston and auxiliary piston, said cylinder being provided with exhaust ports near the head thereof and with intake ports so located and controlled as to be open when the power 30 piston is near the end of its power stroke, said auxiliary piston returning on its in-stroke in advance of the power piston to thereby draw in a new charge through the intake ports and simultaneously expel 35 burnt gases through the exhaust ports, of a sleeve valve for opening and closing said intake and exhaust ports.
- 40 15. In an engine of the character described, the combination with a cylinder and power piston, of a sleeve slidably mounted within said cylinder between the power piston and the walls of the cylinder, said cylinder being provided with intake and exhaust ports and said sleeve controlling said 45 ports, of a scavenging piston within said cylinder, said sleeve being provided with by-passes to thereby permit transference of gases from one side of said scavenging piston to the other.
- 50 16. In an internal combustion engine, the combination with a cylinder, a main piston coöperable therewith, and an auxiliary piston in the cylinder movable with the main piston on the power strokes of the latter, of a movable member disposed outside of said auxiliary piston having by-passes providing communication between the spaces on opposite sides of the auxiliary piston when the latter is near its innermost position, and fluid means co-acting with said auxiliary 55 piston to return the latter on its in-stroke in advance of the return stroke of the main piston.
- 60 17. In an internal combustion engine, the combination with a cylinder, a main piston coöperable therewith, and an auxiliary scavenging piston moving in unison with the main piston on the power stroke of the latter, the auxiliary piston being movable independently of the main piston on its return stroke, of fluid pressure means for imparting said independent movements to the auxiliary piston, and means for automatically regulating the speed of the independent return strokes of the auxiliary piston, said 65 means including a plurality of air passages in stationary and movable elements of the engine, said air passages being adapted to align at certain predetermined points in the cycle of operation of the engine.
- 70 18. In an internal combustion engine, the combination with a cylinder, a hollow power piston and an auxiliary piston interposed between the power piston and the head end of the cylinder, said auxiliary piston having a portion thereof extending and movable within said hollow power piston, the auxiliary and power pistons moving together on the power strokes, of means in axial alignment with the cylinder and pistons for actuating the auxiliary piston independently of and in advance of the power piston on the return strokes, and automatically variable means for governing the speed of the independent return strokes of the auxiliary piston, said last named means including a member slidably mounted within the cylinder and having an air passageway adapted to provide communication between the atmosphere and the interior of the power piston to thereby allow discharge of air from within the power piston during the independent movements of the auxiliary piston and its said portion disposed within the power piston.
- 75 19. In witness that I claim the foregoing I have hereunto subscribed my name this 2nd day of April 1915.
